UNITED STATES PATENT OFFICE.

RUFUS G. WASHINGTON, OF CHICAGO, ILLINOIS.

FOLDING TABLE.

1,279,620.

Specification of Letters Patent. Patented Sept. 24, 1918.

Application filed October 27, 1917. Serial No. 198,906.

To all whom it may concern:

Be it known that I, RUFUS G. WASHINGTON, a citizen of the United States, residing at Chicago, in the county of Cook and State 5 of Illinois, have invented certain new and useful Improvements in Folding Tables, of which the following is a specification, reference being had to the accompanying drawings.

10 This invention relates to certain improvements in folding tables and it is an object of the invention to provide a novel and improved device of this general character which may be readily and conveniently folded or collapsed to occupy a minimum of 15 space when not in use and especially when it is desired to transport the table or place the same in storage.

It is also an object of the invention to 20 provide a novel and improved device of this general character wherein the top comprises two hingedly connected sections adapted to fold one upon the other when not in use together with means co-acting with the under 25 surface of the sections for effectively maintaining the same in extended or operative relation.

Furthermore, it is an object of the invention to provide a novel and improved device 30 of this general character including a plurality of supporting members or legs hingedly connected with the table and adapted to be folded thereagainst together with means capable of convenient operation to effectively hold the legs in supporting position.

The invention also has for an object to 35 provide a novel and improved folding table including a container suitably secured to a part of the table and in which the several 40 separable elements such as bolts and the like are adapted to be placed when the table is folded or collapsed so that said elements may be easily accessible when it is desired to arrange the table in extended or operative 45 condition.

The invention consists in the details of construction and in the combination and arrangement of the several parts of my improved folding table wherein certain important 50 advantages are attained and the device rendered simpler, less expensive and otherwise more convenient and advantageous for use, as will be hereinafter more fully set forth.

55 The novel features of my invention will hereinafter be definitely claimed.

In order that my invention may be the better understood I will now proceed to describe the same with reference to the accompanying drawings wherein:

Figure 1 is a view in bottom plan of my improved table as herein embodied, the caster wheels co-acting with the supporting legs being omitted;

Fig. 2 is a longitudinal sectional view 65 taken through the device as illustrated in Fig. 1, the supporting legs or members having caster wheels applied thereto;

Fig. 3 is a view in plan of my improved table in folded or collapsed condition;

Fig. 4 is an enlarged fragmentary sectional view taken substantially on the line 4—4 of Fig. 1;

Fig. 5 is an enlarged fragmentary sectional view taken substantially on the line 75 5—5 of Fig. 1;

Fig. 6 is an enlarged fragmentary sectional view taken substantially on the line 6—6 of Fig. 1;

Fig. 7 is a view in perspective of one of 80 the folding members or beams as herein employed; and

Fig. 8 is a view in perspective of a fabric sheet adapted to be inserted between the opposed faces of the sections of the table 85 when said sections are folded one upon the other.

As herein disclosed the top of my improved table comprises two sections 1 of substantially the same configuration and 90 which have adjacent marginal portions hingedly connected one to the other as indicated at 2 whereby said sections 1 may be readily and conveniently folded one upon the other when the table is not in use. As 95 particularly illustrated in Fig. 2 it is to be noted that the hinge construction 2 is of such a character as to afford no obstruction to the upper surface of the section 1 when in extended position. One of the sections 100 1 at its hinged marginal portion is provided with an extension 3 adapted to underlie the adjacent marginal portion of the second section 1 so that the outward relative movement of the sections 1 is limited and where- 105 by it is assured that the upper surfaces of said sections 1 will be substantially flush and occupy the same plane when in extended relation.

Each of the sections 1 is provided adjacent a longitudinal margin thereof with the depending housing or socket 4 having its

inner faces open and in substantially transverse alinement with the housing or socket 4 each of the sections has hingedly engaged therewith as at 5 a holding member 6 substantially L-shaped in form. When the sections 1 are extended each of the housings or sockets 4 has substantially longitudinally alined therewith a holding member 6.

Each of the housings or socket members 10 4 is adapted to receive an end portion of a supporting member or beam 7 which is of such a length, when in applied position, as to extend beyond the longitudinally alined holding member 6. The outer or under face 15 of the member or beam 7 is provided with a transversely disposed recess or groove 8 in which the angular or foot portion 9 of the holding member is adapted to be seated. The holding member 6 by its frictional engagement 20 with the member or beam 7 will serve to hold said member or beam 7 in applied position although it is to be understood that if desired, the pivotal connection of the member 6 may constitute a spring 25 hinge without departing from the spirit of the present device or adding novelty thereto as the use of such a hinge or its equivalent is well known. By this arrangement it will be at once perceived that the supporting member or beam 7 is effectively maintained 30 in applied position and serves to hold the sections 1 in either extended or operative relation. The intermediate portion of the member or beam 7 has its under faces cut 35 away or reduced as at 10 so that the same may properly bridge the extension 3 carried by the hinged marginal portion of one of the sections 1.

Coacting with the outer end portions of 40 each of the sections 1 are the transversely spaced supporting legs 11 preferably hollow and rectangular in cross section. The legs of each section are so spaced longitudinally of the table as to permit the same to be folded inwardly against the inner faces 45 of the section 1 without said legs interfering one with the other. Disposed over the upper or inner end of each of the legs 11 is a metallic cap 12 which is hingedly connected at its inner margin as indicated at 14 with the under face of the co-acting section 1. Disposed around the upper or inner portion 50 of the leg 11 inwardly of the cap 12 and in close proximity thereto is a band 15 provided with a perforate extension 16 through which is adapted to be extended the outer or free end portion of the shank 17. The shank 17 is also loosely directed through an opening 18 suitably positioned in the co-acting section 1 and the opposite end of 60 said shank is provided with the head 19 which snugly fits within the countersunk portion 20 of the opening 18 at the outer face of the section 1. By this arrangement 65 it will be perceived that the head 19 of the

shank 17 will be flush with the outer surface of the section 1 as is particularly illustrated in detail in Fig. 4. Threaded upon the free end portion of the shank 17 is the nut 21 which is adapted to engage the under or outer face of the extension 16 whereby the leg 11 is effectively held in supporting position. In order to fold the leg 11 it is only necessary to remove the nut 21 and withdraw the shank 18.

Suitably secured to the under face of one of the sections 1 is a comparatively small fabric receptacle 22 provided with an elastic mouth portion 23 which serves to maintain said receptacle normally closed. When the table is to be collapsed or folded the shanks 17 and nuts 21 together with other separable or loose parts are adapted to be placed within such receptacle so that when it is desired to reassemble or extend the table 75 these parts may be readily located. When the table is folded or collapsed the legs 11 of each of the sections 1 fold inwardly and transversely of the sections in opposite directions and in order to maintain the legs 80 in such folded positions I employ a strap 24 suitably secured at one end to the under surface of the section 1 and said strap contacts with a buckle 25 also carried by the under surface of the section 1 but positioned 85 at the outer side of the legs 11 when folded and as is believed to be clearly illustrated in Figs. 1, 2 and 3 of the accompanying drawings.

The marginal portions of each of the sections 1 at a predetermined point inwardly of the edges thereof with the exception of the hinged marginal portion is provided with the depending aprons 26 which serve to enhance the esthetic effect of the table 100 when extended and it is preferred that said aprons 26 be of a width in excess of the transverse diameter of the legs 11 so that when the legs 11 are folded they will be confined within the space defined by the 105 aprons 26. By this arrangement it will be perceived that when the sections 1 are folded one upon the other the aprons 26 afford protection therefor. It should also be understood that if preferred the aprons may 110 be hingedly connected to the section 1 so that the same may also be folded against the under surface of the table when the table is in folded or collapsed arrangement. In order to protect the outer surfaces of the sections 1 which are intended to be highly polished, when said sections are folded one upon the other I find it of advantage to provide the fabric sheet 27 formed of felt or other desirable material and which operates in a 115 manner which is believed to be clearly apparent to those skilled in the art to which my invention pertains.

As particularly illustrated in Fig. 4 I find it of advantage to insert in each end por-

tion of a leg 11 a block 29 of suitable material. It is also my purpose to employ in connection with the lower or outer end portions of each of the supporting members or 5 legs 11 a caster 30 of any preferred type. It will also be understood that if desired the caster 30 may also be placed within the receptacle 23 when the table is folded or collapsed.

10 I also wish to state that the various parts of my improved table may be made of material which best suits conditions and the same may be expensively finished or otherwise. I also wish to state that it is my purpose that all of the metallic parts comprised 15 in my table be highly polished so that it will possess increased attractiveness.

From the foregoing description, it is thought to be obvious that a folding table 20 constructed in accordance with my invention is particularly well adapted for use by reason of the convenience and facility with which it may be assembled and operated and it will also be obvious that my invention 25 is susceptible of some change and modification without materially departing from the principles and spirit thereof and for this reason I do not wish to be understood as limiting myself to the precise arrangement and formation of the several parts 30 herein shown in carrying out my invention in practice except as hereinafter claimed.

I claim:—

1. A folding table including a top consisting of two hingedly connected sections 35 adapted to be folded one upon the other, supporting legs hingedly connected with said sections and adapted to be folded thereagainst, a perforate lateral extension carried by the hinged end portion of each of 40 said legs and positioned below the table top when the leg is in supporting position, and a clamping member disposed through a section of the top and co-acting with said perforate extension for holding the leg in supporting position.

2. A foldable table comprising a top consisting of two sections adapted to fold one upon the other, legs hingedly engaged with 50 said sections, means for holding the legs in supporting position, a socket carried by each of the sections, a holding member pivotally engaged with each of the sections and supporting members underlying the sections 55 when extended and having an end portion insertible in a socket of one of the sections, the holding member of the second section co-acting with the opposite end portion of 60 said member, the hinged marginal portion of one of the sections of the top being pro-

vided with an extension adapted to underlie the adjacent marginal portion of the second section for limiting the relative outward movement of the sections.

3. A foldable table comprising a top consisting of two sections adapted to fold one upon the other, legs hingedly engaged with 65 said sections, means for holding the legs in supporting position, a socket carried by each of the sections, a holding member pivotally engaged with each of the sections and supporting members underlying the sections when extended and having an end portion insertible in a socket of one of the sections, the holding member of the second section 70 co-acting with the opposite end portion of said member, said holding member being substantially L-shaped in form, said supporting member being provided with a recess to receive a foot of the holding member. 75

4. A folding table including a top consisting of two hingedly connected sections adapted to be folded one upon the other, supporting legs hingedly connected with 80 said sections and adapted to be folded thereagainst, a perforate extension carried by the hinged end portion of each of said legs, a clamping member disposed through a section and co-acting with said perforate extension for holding the leg in supported position, the hinged marginal portion of one 85 of the sections being provided with an extension adapted to underlie the adjacent marginal portion of the second section for limiting the relative outward movement of 90 the sections, and means co-acting with said sections for holding the same extended.

5. A folding table including a top consisting of two hingedly connected sections 95 adapted to be folded one upon the other, supporting legs hingedly connected with said sections and adapted to be folded thereagainst, a perforate lateral extension carried by the hinged end portion of each of 100 said legs and positioned below the table top when the leg is in supporting position, a clamping member disposed through a section of the top and co-acting with said perforate extension for holding the leg in supporting position, and means carried by each 105 of the sections and co-acting with the supporting legs for holding said supporting legs in folded position.

In testimony whereof I hereunto affix my signature in the presence of two witnesses. 110
